(57) **CLAIM**

The ornamental design for a portable bidet, as shown and described.

DESCRIPTION

FIG. 1 is a front perspective view of a portable bidet, showing my new design;

FIG. 2 is a rear perspective view thereof;

FIG. 3 is a front view thereof;

FIG. 4 is a rear view thereof;

FIG. 5 is a left side view thereof;

FIG. 6 is an enlarged top view thereof;

FIG. 7 is an enlarged bottom view thereof;

FIG. 8 is a front exploded view thereof;

FIG. 9 is an exploded perspective view thereof;

FIG. 10 is a front view shown in an alternative configuration of use; and,

FIG. 11 is an enlarged detail view of area 11 in FIG. 1.

The broken lines in the drawings illustrate the portions of the portable bidet, which form no part of the claimed design. The dash-dot-dash broken lines encircling the enlarged views are for annotative purposes only and form no part of the claim thereof.
